UNITED STATES PATENT OFFICE.

ISAAC A. HOCKENBERY, OF HIGHTBRIDGE, NEW JERSEY.

CROWN DIRT-SHIELD FOR PLOWS.

No. 802,863.

Specification of Letters Patent.

Patented Oct. 24, 1905.

Application filed March 28, 1905. Serial No. 252,607.

To all whom it may concern:

Be it known that I, ISAAC A. HOCKENBERY, a citizen of the United States, residing in Highbridge, in the county of Hunterdon and State of New Jersey, have invented certain new and useful Improvements in Crown Dirt-Shields for Plows, of which the following is a specification.

The invention has reference to plows, and more especially to an improvement thereof or attachment therefor, as will protect the furrow created by the plow against such remnants of the furrow-slice as may attempt to force their way over the moldboard while the plow is in operation.

It is a design of the invention to manufacture plows in accordance with this invention or to manufacture attachments embodying this invention and which can be placed on plows already manufactured.

An embodiment of the invention is illustrated on the accompanying sheet of drawings, whereon—

Figure 1 illustrates a top plan view, partly in perspective, of a plow with the improvement applied. Fig. 2 illustrates a side elevational view of the same. Fig. 3 illustrates a perspective elevation view looking from the rear of the plow, and Fig. 4 illustrates in perspective the apron adapted to be attached to a plow.

In the several illustrations similar characters of reference indicate similar parts.

The invention may be embodied in a plow while the same is being manufactured or may be applied to plows now in use and which comprehend handles 5, a beam 6, a clevis 7, a moldboard 8, a plowshare 9, and the usual slip-point 10. A fender 11, which in the present instance may be provided with lugs 12 and 13, having openings 14 and 15, may

have the smaller end 16 of it tapering and inserted into a crotch formed by the neck of the beams 6 and the moldboard 8—for instance, as seen in Fig. 2—and this fender may 45 be fastened to the beam, as well as the moldboard, in any suitable manner—such, for instance, as by rivets 17—while of course, as is understood, the fastening of this fender in place may be accomplished in any suitable 50 manner by mounting the same in a brace 18 by having the members 12 and 13 thereof affixed in extensions 19 and 20, which may be carried by said braces and which member may take against the under side of the handles 5 55 at a point behind the plowshare, as seen, for instance, in Fig. 3.

It will now be seen that during the plowing operation and as the furrow-slice is forced upwardly along the moldboard that said slice 60 may be fully overturned away from such moldboard without any of the remnants thereof passing over the edge of the moldboard and dropping into the furrow.

Within the purview of this invention I may 60 vary the construction and assemblage of parts without departing from the spirit thereof.

Having thus described this invention, I claim—

1. In a plow, the combination with a moldboard a handle, and a beam of a tapering fender adapted to be located in the crotch between the moldboard and beam. 70

2. In a plow the combination with a moldboard and a beam, of a fender located between 75 the upper portion of the moldboard and the beam and means to hold the fender in place.

ISAAC A. HOCKENBERY.
